UNITED STATES PATENT OFFICE

FAY T. RODGERS, OF MEMPHIS, TENNESSEE

DESIGN FOR A REFRIGERATOR DISPLAY CASE

Application filed February 6, 1932. Serial No. 42,761. Term of patent 14 years.

To all whom it may concern:

Be it known that I, FAY T. RODGERS, a citizen of the United States of America, residing at Memphis, in the county of Shelby and State of Tennessee, have invented a new, original, and ornamental Design for Refrigerator Display Cases, of which the following is a specification, reference being had to the accompanying drawing, forming part thereof.

Fig. 1 is a perspective view of the front and one end of my refrigerator display case; and

Fig. 2, a perspective view of the rear and

end of the case, in both of which the predominant features are the definite though minor rearward inclination of the front, the L shaped cross section of the top and severely plain polished surfaces outlined by contrasting polished strips or bands.

I claim:

The ornamental design for a refrigerator display case, as shown and described.

In testimony whereof I have hereunto affixed my signature.

FAY T. RODGERS.
